(57) **CLAIM**

The ornamental design for a ventilating and lighting assembly, as shown and described.

DESCRIPTION

FIG. 1 is a perspective view of a ventilating and lighting assembly constructed in accordance with an embodiment of the present invention;

FIG. 2 is a top view of the ventilating and lighting assembly shown in FIG. 1;

FIG. 3 is a front view of the ventilating and lighting assembly shown in FIGS. 1 and 2; and,

FIG. 4 is a side view of the ventilating and lighting assembly shown in FIGS. 1-3.
